UNITED STATES PATENT OFFICE

CALVERT B. COTTRELL, 3D, OF WESTERLY, RHODE ISLAND, ASSIGNOR TO C. B. COTTRELL & SONS COMPANY, OF WESTERLY, RHODE ISLAND, A CORPORATION OF DELAWARE

BED AND CYLINDER PRINTING PRESS

Application filed May 12, 1931. Serial No. 536,801.

The object of my invention is to provide certain improvements in a bed and cylinder printing press whereby the product of the press may be materially increased with a minimum movement of the impression cylinder and form bed.

My invention comprises an impression cylinder which oscillates substantially two revolutions on each of its opposite strokes, said cylinder being operable on each stroke, to successively take, print and deliver two sheets.

My invention more particularly comprises a bed and cylinder printing press having two inking mechanisms, two pairs of opposed sheet feeders and a pair of opposed deliveries, all coacting to feed, print and deliver two sheets for each stroke of the impression cylinder, the sheet feeders being arranged in upper and lower pairs, the first sheet on each stroke being fed to the upper side of the cylinder and the second sheet on each stroke being fed to the under side of the cylinder and one delivery being operable to take the first and second printed sheets on one stroke of the cylinder and the other delivery being operable to take the first and second sheets on the opposite stroke of the impression cylinder.

My invention further comprises a bed and cylinder printing press in which the reciprocating bed carries two forms which coact with two sheet impression surfaces on the coacting impression cylinder.

My invention still further comprises means for alternately raising and lowering the two inking mechanisms whereby their form rollers may be driven continuously in one direction, one inking mechanism being operable for inking the forms on one stroke of the bed and the other inking mechanism being operable for inking the forms on the opposite stroke of the bed.

A practical embodiment of my invention is represented in the accompanying drawings in which:

Fig. 1 represents a detail side elevation of my improved bed and cylinder printing press, the parts being in the positions they

assume when the bed and cylinder have proceeded on their right hand stroke (as the drawings are viewed) until the right hand form is about to print on the sheet which was fed from the upper right hand feeder, the form rollers of the left hand inking mechanism being lowered into position to contact with the forms and the form rollers of the right hand inking mechanism being raised out of position to contact with said forms as the bed proceeds to the limit of its right hand movement; the position of the form bed as it approaches said right hand limit being shown in dotted lines;

Fig. 2 represents an enlarged detail view of one of the tumbler gripper opening pins and its adjacent parts;

Fig. 3 represents an enlarged detail view showing one of the pin operating cams on the form bed;

Fig. 4 represents a detail diagram showing the relative positions of the several parts as the form bed reaches the limit of its left hand stroke and is about to start on its right hand stroke;

Fig. 5 represents a similar view showing the relative positions of the parts in the right hand stroke of the bed as the sheet taken from the upper right hand feeder is about to be printed by the right hand form; the impression cylinder having rotated about one-half of a revolution;

Fig. 6 represents a similar view showing the relative positions of the parts in the right hand stroke of the bed as the next succeeding sheet taken from the lower left hand feeder is about to be printed by the left hand form and the preceding printed sheet is being transferred to its right hand delivery; the impression cylinder having rotated one revolution;

Fig. 7 represents a similar view showing the relative positions of the parts in the right hand stroke of the bed as the second sheet is being transferred to its right hand delivery; the impression cylinder having rotated one and one-half revolutions;

Fig. 8 represents a similar view showing the relative positions of the parts as the bed and cylinder reach the limit of their right

hand stroke; the cylinder having rotated slightly more than two revolutions;

Fig. 9 represents a similar view showing the relative positions of the parts in the left hand stroke of the bed as the third sheet which was taken from the upper left hand feeder is about to be printed by the left hand form; the impression cylinder having rotated about one-half of a revolution;

Fig. 10 represents a similar view showing the relative positions of the parts in the left hand stroke of the bed as the next succeeding sheet taken from the lower right hand feeder is about to be printed by the right hand form and the preceding printed sheet is being transferred to its left hand delivery; the impression cylinder having rotated about one revolution;

Fig. 11 represents a similar view showing the relative positions of the parts in the left hand stroke of the bed as the sheet taken from the lower right hand feeder is being delivered to its left hand delivery; the impression cylinder having rotated one and one-half revolutions;

Fig. 12 represents a detail side elevation partly in diagram with the bed about midway of its stroke, this view more particularly showing the means for opening and closing the several impression cylinder grippers on the opposite strokes of the bed;

Fig. 13 represents a detail plan view of the same;

Fig. 14 represents a detail diagram showing the positions of the parts as the gripper is closed to take the first sheet from the upper right hand feeder;

Fig. 15 represents a similar view showing the relative positions of the parts as the same gripper is opened to transfer the first printed sheet to its right hand delivery;

Fig. 16 represents a similar view showing the relative positions of the parts as the next set of grippers are closed to take the succeeding sheet from the lower left hand feeder; and

Fig. 17 represents a similar view showing the relative positions of the several parts as the grippers are opened to transfer the second printed sheet to its right hand delivery.

The reciprocating form bed is denoted by 1 and its two longitudinally arranged forms by 2, 3. This bed may be reciprocated by any suitable means, not shown herein.

Two inking mechanisms are provided, one for inking the forms on the right hand stroke of the bed and the other for inking the forms on the left hand stroke of the bed. Each inking mechanism comprises an ink fountain 4, distributing rollers 5, form rollers 6 and an electric motor 7, which motor is independent of the bed reciprocating means and drives both the distributing rollers and the form rollers continuously in one direction, to ensure an even application of the ink to the

forms 2 and 3. Any suitable means may be provided for lowering the form rollers 6 of the left hand inking mechanism into position to ink the forms 2 and 3 on the right hand stroke of the bed and for raising the form rollers out of position to contact with said forms on the left hand stroke of the bed, said means in the present instance including a cam plate 8 with yielding oppositely disposed end members 9 and 10. Similarly, any suitable means may be provided for lowering the form rollers 6 of the right hand inking mechanism into position to contact with the forms 2 and 3 on the left hand stroke of the bed and for raising the said form rollers out of position to contact with said forms on the right hand stroke of the bed, said mechanism in the present instance including a cam plate 11 with yielding oppositely disposed end members 12 and 13.

The oscillating impression cylinder 14 is geared at all times to the reciprocating bed 1 through the usual gear and rack connection 15, 16. The movement of the bed is sufficient to rotate the impression cylinder substantially two revolutions in each direction.

This oscillating impression cylinder is provided with two diametrically opposed sets of tumbler actuated grippers 17, 18 for taking, printing and transferring two sheets on one stroke of the impression cylinder and two diametrically opposed sets of tumbler actuated grippers 19 and 20 for taking, printing and transferring two sheets on the opposite stroke of the impression cylinder. The adjacent oppositely directed grippers 17 and 19 are arranged to take sheets at the proper times from two opposed sheet feeders 21, 22 at the upper side of the impression cylinder and the adjacent oppositely directed grippers 18 and 20 are arranged to take sheets at the proper times from two opposed sheet feeders 23, 24 at the lower side of the impression cylinder. Two opposed sheet deliveries 25 and 26 are provided, the right hand sheet delivery 25 being arranged to take the printed sheets from the grippers 17 and 18 respectively on the right hand stroke of the bed and the left hand sheet delivery 26 being arranged to take the printed sheets from the grippers 19 and 20 upon the left hand stroke of the bed.

The usual sheet feed stops 27, 28, 29, 30 are provided for the sheet feed tables 21, 22, 23, 24 respectively, which sheet feed stops may be operated in the usual manner from the reciprocating bed by means not shown herein.

The sheet strippers 31, 32 for the right and left hand deliveries 25 and 26 may be operated from the reciprocating bed at the proper times by means not shown herein.

Any suitable means may be employed for opening and closing the grippers on the impression cylinder at the proper times for taking and transferring their sheets. In the

present instance on one side of the bed I provide a cam 33 for closing the grippers 17 to take its sheet from the upper right hand feeder 21; a cam 34 for opening the grippers 17 to permit the transfer of the sheet to the right hand delivery 25; a cam 35 for closing the grippers 18 to take its sheet from the lower left hand feeder 23, and a cam 36 for opening the grippers 18 to permit the transfer 10 of the sheet to the right hand delivery.

Similarly, I provide on the other side of the bed a cam 37 for closing the grippers 19 to take its sheet from the upper left hand feeder 22; a cam 38 for opening the grippers 19 to transfer the printed sheet to the left hand delivery 26; a cam 39 for closing the grippers 20 to take its sheet from the lower right hand feeder 24, and a cam 40 for opening the grippers 20 to transfer the 20 sheet to the left hand delivery 26.

These cams 33 to 40 inclusive are illustrated in Figs. 12 to 17 inclusive. As all of the gripper tumbler actuating devices are the same, one only has been illustrated in Figs. 2 25 and 3, viz., the device for opening the grippers 17. The tumbler actuating pin 42 is slideable into the path of the tumbler cam 41 for the grippers 17 at the proper time, to close the grippers 17 on the sheet fed from the upper right hand feeder 21. This pin is held yieldingly out of the path of the cam by the spring 43. The pin operating rock lever is pivoted at 44 to the main frame and it has one arm 45 which engages the pin to move it 30 laterally into the path of the tumbler cam 41 and another arm 46 arranged in position to ride over the yielding cam 33 as the bed moves to the right and under the cam as the bed moves to the left.

From the above description it will be seen 40 that I have provided means whereby two sheets may be taken, printed and delivered on each stroke of the impression cylinder and bed, certain of the sheets being taken from the two oppositely disposed upper feeders and the others of the sheets being taken from the two oppositely disposed lower feeders, the sheets taken and printed on one stroke of the cylinder being transferred to one delivery 45 and the sheets taken and printed on the other stroke of the cylinder being transferred to the opposite delivery. This arrangement permits a maximum product to be fed, printed and delivered with a minimum movement of 50 the bed and cylinder. Furthermore, by the provision of two inking mechanisms having their distributing and form rollers driven continuously in one direction only, the proper application of the ink to the forms on each 55 stroke of the bed is ensured.

It is evident that various changes may be 60 resorted to in the construction, form and arrangement of the several parts without departing from the spirit and scope of my invention, and hence I do not intend to be

limited to the particular embodiment herein shown and described, but

What I claim is:

1. In a bed and cylinder printing press, a reciprocating bed, an oscillating impression cylinder operable, on each stroke, to successively take, print and deliver two sheets, and two inking mechanisms, one operable on one stroke and the other operable on the opposite stroke of the bed. 75

2. In a bed and cylinder printing press, a reciprocating bed bearing two forms, an oscillating impression cylinder having two impression surfaces and operable, on each stroke, to successively take, print and deliver 80 two sheets, and two inking mechanisms, one operable to ink both forms on one stroke and the other operable to ink both forms on the opposite stroke of the bed.

3. In a bed and cylinder printing press, a reciprocating form bed, an oscillating impression cylinder operable, on each stroke, to successively take, print and deliver two sheets, and four sheet feeders, two arranged to feed sheets from opposite directions to the upper 90 side of the impression cylinder and two arranged to feed sheets from opposite directions to the under side of the impression cylinder. 95

4. In a bed and cylinder printing press, a reciprocating form bed, an oscillating impression cylinder operable, on each stroke, to successively take, print and deliver two sheets, four sheet feeders, two arranged to feed sheets from opposite directions to the upper side 100 of the impression cylinder and two arranged to feed sheets from opposite directions to the under side of the impression cylinder, and two deliveries arranged to take their printed sheets from the upper side of the impression cylinder in opposite directions. 105

5. In a bed and cylinder printing press, a reciprocating bed bearing two forms, an oscillating impression cylinder having two impression surfaces and operable, on each stroke, to successively take, print and deliver 110 two sheets, two inking mechanisms, one operable to ink both forms on one stroke and the other to ink both forms on the opposite stroke of the bed, and four sheet feeders, two arranged to feed sheets from opposite directions to the upper side of the impression cylinder and two arranged to feed sheets from opposite directions to the under side of the impression cylinder. 115

6. In a bed and cylinder printing press, a reciprocating bed bearing two forms, an oscillating impression cylinder having two impression surfaces and operable, on each stroke, to successively take, print and deliver two sheets, two inking mechanisms, one operable to ink both forms on one stroke and the other to ink both forms on the opposite stroke of the bed, four sheet feeders, two arranged to feed sheets from opposite directions to the upper side of the impression cylinder. 120

inder and two arranged to feed sheets from opposite directions to the under side of the impression cylinder, and two deliveries arranged to take their printed sheets from the upper side of the impression cylinder in opposite directions.

7. In a bed and cylinder printing press, a reciprocating form bed, an oscillating impression cylinder operable, on each stroke, to successively take, print and deliver two sheets, and means for feeding the first and second sheets of each stroke from opposite sides of the cylinder.

8. In a bed and cylinder printing press, a reciprocating form bed, an oscillating impression cylinder operable, on each stroke, to successively take, print and deliver two sheets, and means for feeding the first and second sheets of each stroke from opposite sides of the cylinder to the upper and under sides respectively of the cylinder.

9. In a bed and cylinder printing press, a reciprocating form bed, an oscillating impression cylinder operable, on each stroke, to successively take, print and deliver two sheets, means for feeding the first and second sheets of each stroke from opposite sides of the cylinder, and two deliveries, one for taking the two successively printed sheets on one stroke and the other for taking the two successively printed sheets on the opposite stroke of the cylinder.

10. In a bed and cylinder printing press, a reciprocating form bed, an oscillating impression cylinder operable, on each stroke, to successively take, print and deliver two sheets, means for feeding the first and second sheets of each stroke from opposite sides of the cylinder to the upper and under sides respectively of the cylinder, and two deliveries, one for taking the two successively printed sheets from the upper side of the cylinder in one direction on one stroke and the other for taking the two successively printed sheets from the upper side of the cylinder in the opposite direction on the opposite stroke.

11. In a bed and cylinder printing press, a reciprocating form bed, and an oscillating impression cylinder arranged to oscillate substantially two revolutions in each direction, said cylinder being operable on each stroke to successively take, print and deliver two sheets.

12. In a bed and cylinder printing press, a reciprocating bed bearing two forms, and an oscillating impression cylinder having two impression surfaces, said cylinder being arranged to oscillate substantially two revolutions in each direction and operable, on each stroke, to successively take, print and deliver two sheets.

13. In a bed and cylinder printing press, a reciprocating bed bearing two forms, an oscillating impression cylinder having two impression surfaces, said cylinder being ar-

ranged to oscillate substantially two revolutions in each direction and operable, on each stroke, to successively take, print and deliver two sheets, and two inking mechanisms, one operable to ink both forms on one stroke and the other to ink both forms on the opposite stroke of the bed.

14. In a bed and cylinder printing press, a reciprocating bed bearing two forms, an oscillating impression cylinder having two impression surfaces, said cylinder being arranged to oscillate substantially two revolutions in each direction and operable on each stroke to successively take, print and deliver two sheets, means for feeding the first sheet on each stroke from one side of the cylinder, and means for feeding the second sheet on the same stroke from the opposite side.

15. In a bed and cylinder printing press, a reciprocating bed bearing two forms, an oscillating impression cylinder having two impression surfaces, said cylinder being arranged to oscillate substantially two revolutions in each direction and operable on each stroke to successively take, print and deliver two sheets, means for feeding the first sheet on each stroke from one side of the cylinder to its upper side, and means for feeding the second sheet on the same stroke from the opposite side to the under side of the cylinder.

16. In a bed and cylinder printing press, a reciprocating bed bearing two forms, an oscillating impression cylinder having two impression surfaces, said cylinder being arranged to oscillate substantially two revolutions in each direction and operable, on each stroke, to successively take, print and deliver two sheets, means for feeding the first sheet on each stroke from one side of the cylinder, means for feeding the second sheet on the same stroke from the opposite side, and two deliveries, one for taking the two successively printed sheets on one stroke and the other for taking the two successively printed sheets on the opposite stroke of the cylinder.

17. In a bed and cylinder printing press, a reciprocating bed bearing two forms, an oscillating impression cylinder having two impression surfaces, said cylinder being arranged to oscillate substantially two revolutions in each direction and operable on each stroke to successively take, print and deliver two sheets, means for feeding the first sheet on each stroke from one side of the cylinder to its upper side, means for feeding the second sheet on the same stroke from the opposite side to the under side of the cylinder, and two deliveries, one for taking the two successively printed sheets on one stroke and the other for taking the two successively printed sheets on the opposite stroke of the cylinder.

18. In a bed and cylinder printing press, a reciprocating form bed, an oscillating impression cylinder, two pairs of opposed sheet

feeders, and a pair of opposed deliveries, all coacting to feed, print and deliver two sheets on each stroke of the impression cylinder.

19. In a bed and cylinder printing press, 5 a reciprocating form bed, two opposed inking mechanisms therefor, an oscillating impression cylinder, two pairs of opposed sheet feeders, and a pair of opposed deliveries, all coacting to feed, print and deliver two sheets on 10 each stroke of the impression cylinder.

20. In a bed and cylinder printing press, a reciprocating form bed, an oscillating impression cylinder, upper and lower pairs of opposed sheet feeders, and an intermediate 15 pair of opposed deliveries, all coacting to feed, print and deliver two sheets on each stroke of the impression cylinder.

21. In a bed and cylinder printing press, a reciprocating form bed, two opposed inking 20 mechanisms therefor, an oscillating impression cylinder, upper and lower pairs of opposed sheet feeders, and an intermediate pair of opposed deliveries, all coacting to feed, print and deliver two sheets on each stroke 25 of the impression cylinder.

22. In a bed and cylinder printing press, a reciprocating form bed bearing two forms, an oscillating cylinder having two impression surfaces, said cylinder being operable to take, 30 print and deliver two sheets in substantially two revolutions of the cylinder in each direction, two inking mechanisms, each having its form cylinders continuously driven in one direction, and means for bringing one inking mechanism into position to ink both forms on one stroke of the bed and the other inking mechanism into position to ink both forms on 35 the opposite stroke of the bed.

In testimony, that I claim the foregoing as 40 my invention, I have signed my name this 8th day of May, A. D. 1931.

CALVERT B. COTTRELL, 3D.
